UNITED STATES PATENT OFFICE.

JOHN M. CARVER, OF FAIR FOREST, SOUTH CAROLINA.

WINDLASS WATER-ELEVATOR.

SPECIFICATION forming part of Letters Patent No. 629,769, dated August 1, 1899.

Application filed October 22, 1897. Serial No. 656,030. (No model.)

To all whom it may concern:

Be it known that I, JOHN M. CARVER, a citizen of the United States, residing at Fair Forest, in the county of Spartanburg and State 5 of South Carolina, have invented a new and useful Windlass Water-Elevator, of which the following is a specification.

My invention relates to well-fixtures, and particularly to a windlass water-elevator, and has for its objects to provide a simple, inexpensive, and efficient construction and arrangement of parts wherein the receptacles are arranged to counterbalance each other, and to provide an improved stop mechanism 15 for maintaining the parts in the desired positions.

Further objects and advantages of this invention will appear in the following description, and the novel features thereof will be 20 particularly pointed out in the appended claims.

In the drawings, Figure 1 is a perspective view of a water-elevator constructed in accordance with my invention. Fig. 2 is a vertical sectional view of the same, taken parallel with the axis of the windlass. Fig. 3 is a detail view in elevation of the clutch mechanism. Fig. 4 is a detail view in perspective of the pawl. Fig. 5 is a vertical sectional 30 view of a water-elevator constructed in accordance with my invention, showing a preferred form of bucket and bucket-tilting devices. Fig. 6 is a detail view in perspective of a portion of the preferred trip-bail.

Similar numerals of reference indicate corresponding parts in all the figures of the drawings.

Mounted in suitable bearings in the supporting-frame 1 is a windlass having a drum 2 and an operating crank or handle 3, said drum being traversed by a continuous chain 4, terminally supporting receptacles or buckets 5 and engaged by the sprocket-teeth of the drum.

Arranged contiguous to the paths of the buckets is a trough or receiver 6, having a suitable outlet 7, and contiguous to this trough is mounted a swinging trip-bail 8, of which the longitudinal bar extends continuously 45 from one end of the trough to the other for engagement by trip-fingers 9 on the upper

edges of the walls of the buckets. In the construction illustrated these trip-fingers are curved inwardly or over the buckets at diametrically opposite points midway between the points of attachment of the bucket-bails 10, and the trip-bail, which inclines downwardly when in its normal position, is adapted to swing upwardly over the contiguous edge of the trough when engaged by the trip-finger of a bucket to cause the tilting of the bucket to discharge its contents into the trough, as will be seen by reference to Fig. 2.

The drum is provided with an attached clutch-ring 11, provided at its inner periphery with angular clutch-teeth 12, a guide-groove 13 being formed parallel with the plane of the clutch-ring to separate the series of clutch-teeth from the plane of the contiguous body portion of the drum. Coöoperating with the clutch-ring is a pawl 14, pivotally mounted at its lower end upon the frame and provided at its free end with a double-beveled or rounded detent 15 for engagement with the clutch-teeth. This pawl in order that it may be interlocked with the drum to prevent transverse displacement is provided with a guide-ear 16, arranged in the plane of the said groove of the drum and projecting beyond the opposite sides of the pawl to fit in said groove, and thereby hold the pawl in operative engagement with the clutch-teeth. The pivotal point of the pawl is approximately in the vertical plane of the axis of the drum, whereby the pawl is adapted to be yieldingly held by gravity in an inclined position either to the right or to the left, as shown, respectively, in full and dotted lines in Fig. 3. The detent is square at its outer side and is double-beveled or rounded at its inner side, whereby when the pawl is in the position indicated in full lines in Fig. 3 the drum is adapted to rotate in the direction indicated by the arrow in said figure, but is held by the pawl from rotating in the opposite direction. On the other hand, when the pawl is in the position indicated in dotted lines in Fig. 3 the drum is adapted to rotate in the opposite direction to that indicated by the arrow. Thus the drum may be locked in a position with either of the buckets elevated, and the manipulation of the pawl is facilitated by a terminally-headed

stem 17, which projects through a slot 18 in the frame of the apparatus within reach of the operator.

From the above description it will be understood that in addition to the facility afforded by the clutch mechanism for controlling the position of the drum, and hence of the elevating receptacles or buckets, the manner of supporting the buckets provides for a counterbalanced operation of the mechanism and at the same time provides for increased durability by reason of the continuous-chain connection.

In Figs. 5 and 6 I have shown a pump mechanism constructed in accordance with my invention in so far as the operating mechanism is concerned and illustrating a preferred construction of bucket and tilting devices, wherein in the bucket 5^a is provided at an intermediate point approximately one-third of the depth of the bucket from its top with a transverse bar 10^a, through a central opening 10^b in which extends a hoisting-cable 4^a, in this case consisting of a rope. The bucket is flared toward its top and is provided with an inturned rolled upper edge 9^a, constituting an engaging flange or rim for contact with a forwardly and downwardly inclined hook 9^b on the trip-bail 8^a. This trip-bail is mounted contiguous to a trough 6^a, into which the contents of the buckets are adapted to be discharged, and the swinging movement of the bail is limited by suitable upper and lower stops 8^b and 8^c.

Inasmuch as the preferred form of bucket is axially connected with the hoisting-cable at an intermediate point of the depth of the bucket, it will be seen that the engagement of the rim 9^a of the bucket with one of the hooks of the trip-bail will cause the prompt tilting of the receptacle, and, furthermore, that twisting of the cable will not affect the efficiency of the engagement of said rim with the trip-bail. In other words, the engaging rim being continuous it will be engaged by the hook or projection 9^b of the trip-bail, whether the twisting or untwisting of the cable causes rotation of the bucket or not. The attachment of the hoisting-cable to the bucket is preferably obtained by means of a button or disk 10^c, arranged in contact with the under side of the cross-bar 10^a, and the drum 2^a is provided, to suit the cable, with a cross-sectionally-V-shaped seat 2^b, into the apex of which the cable is crowded to prevent slipping of the cable over the drum.

In practice the trip-bail is preferably fulcrumed at an intermediate point of the depth of the trough, whereby as the bucket rises after engagement with the bail its engaged edge is drawn inwardly over the edge of the trough, and finally after the arm of the bail comes in contact with the upper stop 8^b the strain upon the cable applied by the hoisting devices turns the bucket to arrange its upper edge approximately in alignment with the draft of the cable, and thus discharges the contents of the bucket, the lower edge of the

latter having been sufficiently advanced over the trough to cause said contents to be discharged wholly into the latter.

It will be seen that I have provided a bucket with a continuous unobstructed edge whereby not only is the construction of the bucket simplified, but the position thereof cannot in any way affect the efficiency of engagement of the tilting device therewith. I prefer a hook on the tilter to engage an inturned rib on the edge of the bucket, for the reason that by so doing I can cause the necessary lateral movement of the bucket to carry its discharging edge over the contiguous edge of a trough or receptacle without carrying the bucket any considerable distance above the trough or receptacle. As shown in the drawings, Fig. 5, the stop 8^b limits the upward-swinging movement of the trip-bail immediately after the discharging edge of the bucket has reached a point slightly above and suitably over the edge of the receptacle or trough, thus avoiding lost motion and unnecessary elevation of the bucket.

The construction of clutch and operating mechanisms is identical with that hereinbefore described, the pawl 14 being pivotally mounted at a point vertically under the axis of the spindle of the drum and being adapted for lateral adjustment at its upper free end for engagement with the clutch-teeth 12 in order to lock the drum against rotation in either direction at the option of the operator.

From the above description it will be seen that, particularly in the preferred construction of tilting devices illustrated in Figs. 5 and 6, the bucket is provided with an inturned beaded edge which projects inwardly beyond the plane of the inner surface of the bucket to form a pronounced projection adapted to be engaged at any point by the hook of the trip-bail, and that this inturned rim or bead serves as a bearing-point for the intermediate portion of the hoisting-cable when the bucket is in its tilted position to prevent chafing of the cable, said position of the parts being indicated in full lines in Fig. 5. Thus the inturned beaded edge of the bucket performs the function not only of engaging positively with the hook of the trip-bail, but of a bearing for the cable at a point diametrically opposite to that of the engagement of the trip-bail hook therewith.

Various changes in the form, proportion, and the minor details of construction may be resorted to without departing from the spirit or sacrificing any of the advantages of this invention.

Having described my invention, what I claim is—

1. In an apparatus of the class described, the combination with a windlass having a drum mounted for rotation in opposite directions, and buckets carried by opposite ends of a cable traversing the drum, of an internally-toothed clutch-ring concentric with and carried by the drum, and a single reversible

clutch-pawl pivoted upon a supporting-frame eccentrically with relation to and vertically beneath the axis of the drum and terminally constructed to engage the teeth of said clutch-ring at either side of the plane of the axis of the drum, said clutch-pawl being held by gravity in either of its adjusted positions and having an interlocking connection with said clutch-ring in each of its adjusted positions, 5 to prevent transverse displacement of the pawl with relation to the clutch-ring, substantially as specified.

2. In an apparatus of the class described, the combination of a bucket-supporting drum

15 having a concentric internally-toothed clutch-ring and a contiguous guide-groove, a reversible clutch-pawl having a detent provided with a double-beveled or rounded face at one side, and adapted to engage the clutch-teeth at either side of the plane of the axis of the drum, and a guide-ear extending in opposite directions from the detent and fitting in said guide-groove of the drum in either position of the pawl, substantially as specified.

20 3. In an apparatus of the class described, the combination of a bucket having an unobstructed beaded upper edge consisting of an inwardly-rolled portion of the side wall of the bucket, a transverse bar arranged in the

30 bucket between the planes of its inturned rim and bottom and provided with a central

opening, a hoisting-cable terminally extended through said opening of the bar and provided below the plane thereof with a stop to prevent upward displacement, means for operating the cable, and a swinging trip-bail provided with a downturned hook overhanging the path of the upward movement of the bucket, and adapted to engage said inturned rim at any point of the length thereof, the 35 hoisting-cable, in the tilted position of the bucket, being arranged in contact with the beaded edge at a point diametrically opposite to the point of engagement of said hook, substantially as specified.

40 4. The combination of a bucket having an inwardly-beaded upper edge, a flexible hoisting-cable having a swivel connection with the bucket, upon an axial line below the upper edge thereof, means for operating the cable, and a swinging trip-bail pivoted out of the path of the bucket and having a hook to engage the bead at the upper edge thereof, substantially as specified.

45 In testimony that I claim the foregoing as my own I have hereto affixed my signature in the presence of two witnesses.

JOHN M. CARVER.
